United States Patent Office

Des. 195,425
Patented June 11, 1963

195,425

FOOD MIXER OR THE LIKE

John E. Reed, Glen Ellyn, Ill., assignor to Sunbeam Corporation, Chicago, Ill., a corporation of Illinois

Filed July 13, 1962, Ser. No. 70,926

Term of patent 14 years

(Cl. D44—1)

FIG. 1 is a perspective view of a food mixer or the like embodying my design;

FIG. 2 is a side elevational view thereof;

FIG. 3 is a front elevational view thereof;

FIG. 4 is a rear elevational view thereof;

FIG. 5 is a top plan view thereof; and

FIG. 6 is a bottom plan view thereof.

I claim:

The ornamental design for a food mixer or the like, as shown and described.
